ELECTRICAL SYSTEM FOR INTERNAL
COMBUSTION ENGINESDaniel L. Wertz, Elmira, N. Y., assignor to Eclipse
Machine Company, Elmira, N. Y., a corporation
of New York

Application May 31, 1930, Serial No. 458,024

10 Claims. (Cl. 290—38)

This invention relates to electrical systems for internal combustion engines and more particularly to such systems including automatic starting mechanism in which the automatic starting

5 mechanism and the ignition systems have provisions for preventing unauthorized operation of the power plant. The term "automatic starting mechanism" as used in this specification and the claims appended hereto refers to starting 10 systems of the type which automatically function in case of engine stall to restart the engine without requiring any manual operation.

Means have heretofore been provided for preventing unauthorized use of internal combustion 15 engines by means of lock switches controlling the ignition circuits thereof, the leads from said switches being protected by armored cable or the like. Such devices have also incorporated means for grounding the ignition circuits when 20 the ignition switches were open so as to prevent the use of jumper wires around the switches, or of separate coils or batteries. Automatic starting systems which have been hitherto devised in which the starter is adapted to be automatically 25 operated upon closure of the ignition switch have in general however not been protected further than by the use of some form of lock for the ignition switch.

It is an object of the present invention to provide 30 a novel automatic starting and ignition system for internal combustion engines including novel means for protecting the same against unauthorized use of the power plant.

Another object of the invention is to provide 35 such a system including a lock switch adapted to control the ignition circuit in which the connection from the lock switch to the timing mechanism of the ignition circuit is protected by a theft-resisting sheath.

40 A further object is to provide such a system in which a single lock switch is adapted to control both the ignition system and the actuation of the automatic operating device for the starting mechanism.

45 Another object is to provide such a system in which the automatic operating device for the starting mechanism is connected to the lock switch and/or the timing mechanism by a theft-resisting sheath.

50 A still further object is the provision of such a system in which a lock switch initially controls the automatic operating device, and the operation of the automatic operating device closes the ignition circuit.

55 Another object is to provide such a system in-

cluding a lock switch which is adapted to initiate the actuation of the automatic operating device and thereafter is connected to control the ignition circuit.

Further objects and advantages will be apparent to those skilled in the art from the following description taken in connection with the accompanying drawing in which:

Fig. 1 is a semi-diagrammatic illustration of one embodiment of the present invention; and 10

Fig. 2 is an enlarged sectional detail taken substantially on the line 2—2 of Fig. 1.

In Fig. 1 of the drawing there is illustrated a conventional form of starting and ignition system including a battery 10 having one terminal 15 grounded as at 11 and the other terminal connected by means of a lead 12 through ammeter A, lead 13, automatic cut-out 14 and lead 15 to one terminal of a generator G, the other terminal of which is grounded as indicated at 16. 20 It will be understood that the generator G is suitably connected to be driven by the internal combustion engine, not illustrated, whereby the generator serves to charge the battery during the operation of the engine. 25

An automatic operating device indicated generally at 17 is adapted to actuate a starting motor SM by means of current from battery 10 conducted by a lead 18 to a starting switch 19, 20, 21, through a single turn coil 22 and by a 30 lead 23 to one terminal of said motor, the opposite terminal of which is grounded as indicated at 24. The insulated movable switch member 20 is operated by a solenoid 25 which is arranged to be connected to the battery 10 by means of 35 a lead 26, hinged switch member 27 (Fig. 2), contacts 28, 29, leads 30 and 18. The other terminal of solenoid 25 is connected to the ground by a lead 31, normally closed relay contacts 32, 33 and ground connection indicated at 34. 40

Contact 33 is formed on the end of a relay plunger 35 and is normally held against stationary contact 32 by means such as a spring 36. Contact 33 is also held magnetically in closed position during the operation of the 45 starting motor by the single turn coil 22 which is traversed by the starting current. A magnetic pole piece 22' for coil 22 is provided for controlling the magnetic effect of coil 22 on plunger 35, and is adjustable toward and from 50 said plunger to secure the desired attractive force thereon.

A coil 37 is arranged to surround the plunger 35 and is connected at one end by a lead 38 to the starting motor lead 23 and at its other 55

end to the ground by means of a lead 39. Coil 37 is adapted to open the contact 33 when the current through the single turn coil 22 is sufficiently weakened by the relief of the load on the starting motor when the engine starts. A second coil 40 is also arranged to surround the plunger 35, and is connected at one end by a lead 41 to the generator G and at its other end to the ground through lead 39. This coil is adapted to hold the contact 33 open so long as the generator G is in operation.

The ignition circuit of the internal combustion engine includes a timing mechanism indicated generally at 42 which is connected by means of a lead 43 to a second switch member 44 hinged substantially in alignment with switch member 27 and carrying a contact member 45. Contact member 45 is adapted to cooperate with a fixed contact member 46 which is connected by a lead 47 to a manual lock switch 48 of any suitable type. Switch 48 is connected by a lead 49 to the primary 50 of the ignition coil 51, the opposite end of said primary being connected by a lead 52 to the battery 10.

25 The automatic operating device 17 is provided with a suitable casing such as indicated at 53. Lock switch 48 and timing mechanism 42 are also suitably encased and are connected to casing 53 by theft-resisting sheaths or armored cables 67 and 68 for leads 47 and 43 respectively.

Switch member 27 is preferably hinged to the casing 53 of the automatic operating device as at 54 in Fig. 2, and is suitably insulated therefrom as indicated at 55. Switch member 44 is similarly hinged to said casing and insulated therefrom and is adapted to be moved in a direction to close contact 45 by means of an offset portion 56 of switch member 27 which overlaps the edge of switch member 44 but is insulated therefrom as indicated at 57.

Switch member 27 carries a second contact 60 on the opposite side from contact 28 which is adapted to cooperate with a fixed contact 61 suitably insulated from casing 53 as indicated at 62. Contact 61 is connected to the lock switch 48 by lead 63 whereby initial energization of solenoid 25 is secured upon closure of lock switch 48. Switch member 44 also carries a contact 64 on the opposite side from contact 45 and adapted to cooperate with a fixed contact 65, which is grounded as indicated at 66. Means is provided such as a spring 58 to maintain both switch members with their contacts 28 and 45 open and contacts 60 and 64 normally closed, said spring being connected to and insulated from the casing 53 by suitable means such as an angle bracket 59.

Switch members 27 and 44 are formed of magnetic material and are located opposite fixed pole pieces 69 and 70 of solenoid 25 and coils 37 and 40 respectively. Energization of solenoid 25 accordingly will move switch member 27 in a direction to open contact 60 and close contact 28. It will be understood that contacts 61 and 65 may, if deemed desirable, be yieldably mounted as by means of short spring strips in order to effect closure of contacts 28, 29 before opening of contacts 60, 61. The overlapping portion 56 of switch member 27 moves switch member 44 in a direction to open contact 64 and close contact 45. Energization of coils 37 and/or 40 will attract switch member 44 to open contact 64 and close contact 45.

In operation, and starting with the parts in the positions illustrated, closure of lock switch

48 by the operator completes a circuit from battery 10 through lead 52, primary 50 of ignition coil 51, lead 49, switch 48, lead 63, contacts 61, 60, switch member 27, lead 26, solenoid 25, lead 31, contacts 32, 33 to the ground at 34. The consequent energization of the solenoid 25 attracts switch member 27, closing contact 28. This completes a direct connection from the battery 10 to solenoid 25 through lead 30 to contact 29 whereby the solenoid 25 is fully energized by the battery 10. Starting switch member 20 is thereupon drawn into contact with switch members 19 and 21, thus completing the starting circuit from battery 10 through lead 18, switch members 19, 20, 21, single turn coil 22 and lead 23 to the starting motor SM, the circuit being completed through the ground at 24. At this time the coil 37 is also energized from the starting motor circuit through leads 38 and 39 to the ground, so that this coil tends to move the contact 33 into open position, but this is prevented by the single turn coil 22 while the latter is being traversed by the heavy starting current.

25 The switch member 27 when attracted by solenoid 25 also carries with it switch member 44 causing the opening of contact 64 and closure of contact 45. This completes the ignition circuit from battery 10 through lead 52, coil 51, lead 49, switch 48, lead 47, contacts 46, 45, switch member 44 and lead 43 to the timing mechanism 42. The energization of coil 37 also attracts switch member 44 to close contact 45, so that the mechanical connection 56 between the switch members 27 and 44 may be omitted if so desired.

35 When the engine starts, the load on the starting motor is relieved, thus greatly reducing the current traversing the starting circuit. This weakens the effect of the single turn coil 22 and at the same time raises the voltage applied to the coil 37 whereby the coil 37 is enabled to open the contact 33 thus breaking the circuit through solenoid 25. Switch member 20 is thereupon moved to its open position by means of spring 71, thus disconnecting the battery from the starting motor and from coil 37. Coil 37 however retains sufficient magnetism to hold contact 33 in its open position and contact 45 in its closed position by reason of a small amount of current generated by the armature of the starting motor spinning by momentum in its residual field. This current flows through coil 37 to the ground at 39, and suffices to retain contacts 33 and 45 in running position altho it is not strong enough to have any appreciable depolarizing effect on the residual field of the motor. Before the motor armature has stopped spinning, the generator G driven by the engine has built up sufficient voltage to energize coil 40 and thus retain contact member 33 open, and contact 45 closed, to maintain the ignition circuit closed as long as the engine is in operation. When the engine stops for any reason, the coil 40 is deenergized and allows the springs 36 and 58 to expand, thereby closing contact 33 and opening contact 45. If the lock switch 48 has been left in its closed position, solenoid 25 will thereupon be energized and the starting operation will be repeated.

40 In case the engine makes a false start and then stops after the first explosion or two, the relay contact 33 is opened by the relief of the load on the motor, but the generator G is not rotated sufficiently by the engine to build up and operate coil 40 to hold the contacts 33 and 45 in

running position. The coil 37 then serves as above explained to hold said contacts in running position till the starting motor comes substantially to rest, whereupon the contacts are released and the starting operation repeated.

To stop the engine and lock the device against unauthorized operation, it is merely necessary to manipulate the lock switch 48 to its open position as illustrated, whereupon the ignition and

10 starting circuits are opened and the timing mechanism 42 is grounded through lead 43, contacts 64 and 65 and the ground connection 66. Under these circumstances, it will be apparent that the operation of the engine will be impossible without dismantling the timer and substituting a new one therefor or cutting open the casings or protective sheaths. Since these elements are intended to be constructed of highly resistant material, it is evident that these operations would be sufficiently difficult to deter the unauthorized use of the power plant.

Although but one embodiment of the invention has been shown and described in detail, it will be understood that this embodiment is not exclusive, and that changes may be made in the details of construction and dimensions of the parts and substitutions may be made in the form and arrangement of the elements without departing from the spirit of the invention.

30 Reference will therefore be had to the claims hereto appended for a definition of the scope of the invention.

What is claimed is:—

1. In an electrical system for internal combustion engines, a starting circuit including a motor and a magnetic starting switch, an ignition circuit including an ignition switch, a manual switch for controlling the magnetic starting switch, means whereby energization of the 35 starter switch closes the ignition switch, and means for causing the starter switch to open when the engine starts, said last means being arranged to maintain said ignition switch closed as long as the engine is in operation.

45 2. In an electrical system for internal combustion engines, a starting circuit including a motor and a magnetic starting switch, an ignition circuit including an ignition switch, a manual switch in series with said ignition switch and arranged for energizing the magnetic starter switch, means whereby closure of the starter switch causes closure of the ignition switch, and means for opening the starter switch when the engine starts and for maintaining said starter 50 switch open as long as the engine is in operation, said means for maintaining the starter switch open being also arranged to maintain said ignition switch closed.

55 3. In an automatic starting system for internal combustion engines, a starting circuit including a motor and a switch, an automatic operating device for the switch, a manual lock type switch for energizing said automatic operating device, a timing mechanism for the ignition system, a casing for said automatic operating device, an ignition switch within said casing and arranged to be operated by said automatic operating device, theft resisting metallic sheaths connecting the lock switch and the timing mechanism to said casing, and means including contacts arranged to ground said timing mechanism when the ignition switch is open.

70 4. In an electrical system for internal combustion engines, an automatic starting circuit including a motor and a starting switch, an

ignition circuit, a manual lock switch, means whereby said lock switch initially controls said starting switch and thereafter controls said ignition circuit, protective sheathing for said ignition circuit and said lock switch to prevent unauthorized operation of the engine, and means for automatically grounding the ignition circuit, except during the starting and running of the engine.

5 5. In an electrical system for internal combustion engines, an automatic starting circuit including a motor and a starting switch, an ignition circuit, a manual lock switch, means whereby said lock switch initially controls said starting switch and thereafter controls said ignition circuit, protective sheathing for said ignition circuit and said lock switch to prevent unauthorized operation of the engine, and a ground switch for the ignition circuit said switch being normally closed but being opened by the closing of said starting switch.

10 6. In an electrical system for internal combustion engines, a starting circuit including a battery, a motor, and a starting switch, an ignition circuit, an automatic operating device for said starting switch including electro-magnetic means for closing the starting switch, means including a manual switch for causing the energization of said closing means, means including contacts operated by said electro-magnetic means for maintaining the energization of said closing means, and means operated by said closing means for completing said ignition circuit through said manual switch.

15 7. In an electrical system for internal combustion engines, a starting circuit including a motor and a starting switch, an ignition circuit, an automatic operating device for said starting switch including means for closing the starting switch and means for deenergizing said closing means while the engine is in operation, manual means for causing the energization of said closing means, means operated by said closing means for maintaining the energization of said closing means, and means for completing said ignition circuit adapted to be operated by said closing means, said ignition circuit completing means being retained in operative position by said deenergizing means while the engine is in operation, irrespective of said closing means.

20 8. In an electrical system for internal combustion engines, a starting circuit including a motor and a starting switch, an ignition circuit including an ignition switch, a solenoid for closing the starting switch, a magnetic relay switch for deenergizing said solenoid while the engine is in operation, a manual lock switch adapted to control the initial energization of said solenoid, means operated by said solenoid for maintaining said solenoid energized during the starting operation and for closing said ignition circuit through said lock switch, and means operated by said relay magnet for maintaining said ignition circuit closed through said lock switch irrespective of the deenergization of said solenoid.

25 9. In an electrical system for internal combustion engines, a starting circuit including a motor and a starting switch, an ignition circuit including an ignition switch and timing mechanism, a solenoid for closing the starting switch, a magnetic relay switch for deenergizing said solenoid while the engine is in operation, a manual lock switch adapted to control the initial energization of said solenoid, means operated by said solenoid for maintaining said solenoid energized

during the starting operation and for closing said ignition circuit through said lock switch, means operated by said relay magnet for maintaining said ignition circuit closed through said lock switch irrespective of the deenergization of said solenoid, and theft-resisting sheaths connecting the lock switch and automatic switches to the timing mechanism.

10. In an electrical system for internal combustion engines, a starting circuit including a motor and a magnetic starting switch, an ignition circuit including an ignition switch and

timing mechanism, a casing for said starting and ignition switch, a manual lock type switch for controlling the magnetic starting switch, means whereby energization of the starting switch closes the ignition switch, means causing the starting switch to open when the engine starts, said last means being arranged to maintain said ignition switch closed as long as the engine is in operation, and theft resisting sheaths connecting the lock switch to the casing and the casing to the timing mechanism. 5 10
